UNITED STATES PATENT OFFICE.

CHAUNCEY C. WOODWORTH, OF ROCHESTER, NEW YORK.

DESIGN FOR GLASS BOTTLES.

Specification forming part of Design No. 7,600, dated July 28, 1874; application filed July 20, 1874.
[Term of Patent 3½ years.]

To all whom it may concern:

Be it known that I, CHAUNCEY C. WOODWORTH, of the city of Rochester, in the county of Monroe and State of New York, have invented a new and original Design in Bottles; and I do hereby declare that the following is a full, clear, and exact description of the same, reference being had to the accompanying drawing, which represents a perspective view of the bottle.

My invention consists of a bottle in the form of a monkey in a sitting posture, as hereinafter shown and described.

In the drawing, a represents the body, b the legs, c the arms, and d the head, of the animal. f is an ordinary bottle-neck or nozzle, which surmounts the head and receives the stopper.

The body is in a sitting posture, with the head erect. The legs are bent in front of the body, with the feet resting upon the support on which the bottle stands, while the arms rest horizontally, or nearly so, on the breast, as shown.

This bottle is designed specially for holding perfumes and hair-oils.

What I claim is—

The design for a bottle in the form of a sitting monkey, as herein shown and described.

In witness whereof I have hereunto signed my name in the presence of two subscribing witnesses.

CHAUNCEY C. WOODWORTH.
